MEDICAL DIVIDER

Carl G. Geissler, Alameda, Calif.

Application December 5, 1944, Serial No. 566,761

3 Claims. (Cl. 33—192)

1

This invention has to do generally with an improved device for dividing a lineal extent into equal divisions or equidistant points, and relates particularly to a novel medical divider especially adaptable for use in determining equidistant points along a limb, for example along the forearm or lower leg.

For certain purposes, as in the making of one type of metabolism determinations, it is necessary to divide the distance between spaced locations along the arm or leg into a plurality of equidistant points. The distance between corresponding locations, e. g. the wrist and elbow, on the limbs of different individuals of course varies. Accordingly, any quickly useable divider must be capable of such manipulation as will compensate for variations in the distances to be divided.

My primary object is to provide a divider of simple and economical construction capable of easy application and quick manipulation to accurately determine the desired equal divisions of the length being investigated. Another aim is to adapt the divider parts for inexpensive quantity production by die cutting out of transparent sheet Celluloid or plastic materials.

In its preferred form the present invention comprises a pair of relatively movable flexible and flat surface sections having edge portions adapted to intersect at equal and variably spaced points. For this purpose, one section is formed with a straight edge and the other with angular, parallel and equally spaced edges adapted to be intersected by the straight edge to establish the points of division. A further and particular feature is the pivotal association or interconnection of the sections at the location of application of one end portion of the divider to the joint bone of a limb to establish one limit of the distance to be divided. In this connection the invention contemplates suitably adapting the divider at the location of the section pivot, to apply to or fit the joint bone, as by providing a recess in the adjacent divider section.

The invention will be more fully understood from the following description of a preferred embodiment illustrated in the accompanying drawing typically as applied to the determination of points of equal spacing along the forearm. In the drawing:

Fig. 1 is a view illustrating the divider and its use in determining equidistant points along the forearm of a patient;

Fig. 2 is a fragmentary enlarged view showing the pivoted end connection between the divider sections; and

2

Fig. 3 is a cross-section on line 3—3 of Fig. 2.

Referring to Fig. 1, the divider, generally indicated at 10, comprises a pair of relatively movable sections 11 and 12 which, as previously indicated, preferably are made by die cutting them from flexible transparent sheet Celluloid or like material. Ordinarily the length of the divider will be as great as the distances to be divided between the patient's wrist bone and elbow, or angle bone and knee. The outer divider section 11 has a straight edge 13 adapted to be brought into intersecting relation with edges of the base section 12, as will appear.

Section 12 is shaped to provide a plurality of angular parallel spaced edges 14, 15, 16 and 17, four being shown as typical although the number thereof may be varied in accordance with the number of equal linear divisions to be determined.

The lengths of edges 14 to 17 are shown to be of an increasing order toward the elbow end of the divider, in order that within the range of its pivotal adjustment in accommodating different arm lengths, the straight edge 13 will intersect all of these parallel edges of section 12.

25 The sections may be pivotally associated or joined at 18 in any suitable manner, as by providing section 12 with a projection 19, see Fig. 3, extending through an opening 20 in section 11 and headed over the outer surface of the latter to

30 pivotally retain the sections. Means is provided at the pivotal connection 18 for accommodating or fitting the divider to a joint bone of the patient, for example the wrist bone as the divider is shown to be used in Fig. 1. For this purpose, the under-
35 side of section 12 may carry a projection 21 containing a concave opening or recess 22 which is adapted to be fitted over the wrist bone so as to substantially center the pivot with relation thereto.

40 In the use of the divider, recess 22 is applied to the wrist bone as stated, and the sections are pivotally adjusted so that the straight edge 13 and edge 17 intersect at 23, at a location substantially at the end of the elbow or any other part thereof.

45 The location of edge 14 is such that the distance from the center of the pivot 18 to and along a line normal to a projected line of edge 14 corresponds to the equal spacing of the parallel edges 14 to 17. Accordingly, the distance between the wrist bone and location 23 will in all instances be divided into equidistant points at the intersections of the straight edge 13 with the parallel edges, regardless of the total distance between the wrist bone and point 23.

50 As will be apparent, the divider is capable of

easy application and quick manipulation to establish the location of the equidistant points of intersection, which may be indicated by markings at the intersecting edges.

I claim:

1. A measuring device comprising a pair of relatively movable members, one having a straight edge and the other having a series of tooth-shaped portions presenting spaced parallel edges intersecting said straight edge, said members upon relative movement indicating at the intersections of said straight and parallel edges variably but equally spaced alined points, and means associating said members for relative pivotal movement.

2. A measuring device comprising a pair of relatively movable members, one having a straight edge and the other having a plurality of spaced parallel edges intersecting said straight edge, said members upon relative movement indicating at the intersections of said straight and parallel edges variably but equally spaced alined points, and means associating said members for relative pivotal movement at a recess in one of the members applicable to a joint bone.

3. A measuring device comprising a pair of

elongated flat surface members formed of translucent flexible material, one of the members overlying and engaging the other member, means associating corresponding end portions of said members for relative pivotal movement, one member having a straight edge and the other having a plurality of spaced parallel edges intersecting said straight edge, said members upon relative pivotal movement indicating, at the intersections of said straight and parallel edges variably but equally spaced alined points.
